UNITED STATES PATENT OFFICE.

JOHN B. ADLER, OF AURORA, ILLINOIS, ASSIGNOR TO LYON METALLIC MANUFACTURING COMPANY, OF AURORA, ILLINOIS, A CORPORATION OF ILLINOIS.

DESIGN FOR A CHAIR.

Application filed May 18, 1927. Serial No. 22,028. Term of patent 14 years.

To all whom it may concern:

Be it known that I, JOHN B. ADLER, a citizen of the United States, residing at Aurora, Kane County, Illinois, have invented a new, original, and ornamental Design for Chairs, of which the following is a specification, reference being had to the accompanying drawing, forming part thereof.

Attention is hereby called to my co-pending application covering mechanical features of this chair filed May 25, 1927, Serial No. 194,204.

I claim:

The ornamental design for a chair as shown.

JOHN B. ADLER.
